Elyria, Ohio

Application May 18, 1944, Serial No. 536,134

3 Claims. (Cl. 299—110)

1

The present invention relates to a fire fighting implement comprising a spearhead nozzle adapted for penetrating walls, ceilings, the sides of an airplane fuselage, and other objects for the purpose of introducing a stream of water or chemical to the interior of a burning structure.

An important object of the present invention is to provide a spearhead nozzle of this character adapted for connection on a pipe section by means of which the nozzle may be driven through a wall of a burning structure, the spearhead formation of the nozzle serving to retain the latter in position in the wall without necessitating the holding of the same by the fireman.

The invention further comprehends the construction of a nozzle of this character adapted for attaching to a fire fighting axe having a hollow handle adapted for supplying water to the nozzle and by means of which the nozzle may be driven into the wall of a burning structure through the usual action of swinging the axe.

A still further object is to provide a nozzle of this character to which a funnel member may be attached for fighting open fires.

An additional object is to provide a device of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a side elevational view of the nozzle.

Figure 2 is a longitudinal sectional view therethrough.

Figure 3 is an end elevational view.

Figure 4 is a side elevational view showing the funnel member attached to the nozzle and with parts broken away and in section.

Figure 5 is a fragmentary side elevational view of the nozzle attached to a fire fighting axe.

Referring now to the drawing in detail, and first with respect to the form of the invention illustrated in Figures 1 to 3, inclusive, the numeral 5 designates the nozzle generally, which is of tapering form having longitudinally extending cutting edges 6 formed on the sides of the nozzle and spaced circumferentially at substantially 90 degrees from each other, as shown in Figure 3 of the drawing. The front ends of the cutting edges 6 taper to a substantially sharpened point 7

and the cutting edges 6 are longitudinally rounded, as shown in Figures 1 and 2, substantially in the form of a spearhead which is wider at its central portion.

5 The sides of the nozzles between adjacent cutting edges 6 are curved to form channels 8 and the front portions of the channels are formed with elongated recesses 9 tapering toward their front ends and with the rear portions of which orifices 10 communicate leading from the chamber 11 at the interior of the nozzle.

The rear end of the nozzle is formed with a threaded stem 12 to which one end of a pipe 13 may be attached by means of a union or coupling 14.

15 A collar 15 is threaded on the stem 12 between the rear end of the nozzle and the union 14 and the collar may be of hexagonal form to receive a wrench and the collar may be cast integral with the nozzle 5, or may be constructed as a separate unit and secured thereto by means of a set screw 16.

20 The collar 15 may also be externally threaded, as shown at 17 in Figure 4, for threaded connection with the rear end of a funnel member 18 into which the nozzle projects for use in extinguishing outside fires.

25 By attaching the nozzle 5 to the end of a pipe section 13, the same may then be used as a spear 30 or harpoon for driving the nozzle into the wall of a burning object or structure, the spearhead formation of the nozzle serving to retain the nozzle in position in the wall without necessitating the holding of the same by a fireman. Water 35 or suitable chemicals may then be discharged through the nozzle for extinguishing the fire on the interior of the structure.

The pipe section 13 may be covered with a hose or other material, as shown at 19 in Figure 4.

40 In Figure 5 of the drawing we have illustrated a fire fighting axe 20 to the head of which the nozzle 5 may be attached by threading the stem 12 therein, the axe being provided with a hollow handle 21 and the head 20 likewise being hollow 45 to provide communication or connection between the handle and the nozzle. In using this form of the invention, the axe may be swung in the usual manner for driving the nozzle into the wall of an object for extinguishing the fire therein.

50 It is believed the details of construction and manner of operation and advantages of the device will be readily understood from the foregoing without further detailed explanation.

Having thus described the invention, what we 55 claim is:

1. A fire fighting nozzle adapted to be attached to a conduit for fire-extinguishing fluid comprising a spearhead-shaped hollow body, a plurality of longitudinally extending cutting edges formed on the body, said body having longitudinally extending channels in the sides thereof between said cutting edges, said channels having recesses in the front ends thereof and orifices communicating with the recesses leading from the interior of the body.

2. A fire fighting nozzle adapted to be attached to a conduit for fire-extinguishing fluid comprising a spearhead-shaped hollow body, a plurality of longitudinally extending arcuate, diametrically opposed cutting edges formed longitudinally on the body, defining longitudinally extending chan-

nels in the sides of the body, said channels having recesses in the front ends thereof and orifices communicating with the recesses leading from the interior of the body.

5 3. A fire fighting nozzle adapted to be attached to a conduit comprising a spearhead-shaped hollow body, a plurality of longitudinally extending cutting edges formed on the body, said body being concaved between said cutting edges, and having 10 longitudinal recesses in the front ends of the concave portions of the body and orifices communicating with the recesses leading from the interior of the body.
